JOHN MICELS.

UNITED STATES PATENT OFFICE.

AUGUSTIN LE PRINCE, OF NEW YORK, N. Y.

DESIGN FOR WALL-PAPER.

SPECIFICATION forming part of Design No. 15,075, dated June 17, 1884.

Application filed April 11, 1884. Term of patent 3½ years.

To all whom it may concern:

Be it known that I, AUGUSTIN LE PRINCE, a citizen of the Republic of France, residing in the city of New York, county and State of New York, have invented and produced a new and original Design for a Wall or Ceiling Covering, which is especially intended as a wall-hanging, of which the following is a specification.

- 10 The drawing represents a front plan view of the design. This design is in the Byzantine style; and it consists of a regular repetition of the figure of four crescents, *a a a a*. One point of each crescent radiates from a common center, where a button, *b*, is placed. The other point of each crescent rests on the outside limb of the crescent next opposed to it. The general effect of this combination is that of the corolla of a flower. The intermediate space between the corolla-like figures is occupied by a Greek

cross, *c*, the center of which is opened out in the form of a diamond. The space between the arms of the cross is filled in with four pyramids.

25 Although the design is especially intended as a wall-hanging, it will be found useful as a filling for many purposes.

I claim—

The design herein shown and described, consisting of a repetition throughout the design at substantially regular intervals of the corolla-like figures formed of the crescents *a*, the intermediate space between the corolla-like figures being partially occupied by the figure 30 of a Greek cross, and with a background of pyramidal-shaped figures.

AUGUSTIN LE PRINCE.
